DESIGN FOR A NECKLACE

John Rubel, New York, N. Y.

Application April 30, 1945, Serial No. 119,307

Term of patent 7 years

(Cl. D45—16)

To all whom it may concern:

Be it known that I, John Rubel, a citizen of the Republic of France, residing in New York city, in the county of New York and State of New York, have invented a new, original, and ornamental Design for a Necklace, of which the following is a specification, reference being had to the accompanying drawing, forming part thereof.

Fig. 1 is a front elevational view of a necklace showing my new design, and

Fig. 2 is an edge view thereof.

The characteristic features of my design reside in the portions shown in full lines. A part of the necklace is broken away for illustrative purposes.

I claim:

The ornamental design for a necklace, substantially as shown and described.

JOHN RUBEL.
